[57] CLAIM

The ornamental design for a set of price indicating numerals, substantially as shown.

DESCRIPTION

FIG. 1 is a perspective view of a set of price indicating numerals showing my new design;

FIG. 2 is a side elevational view of the right hand side of the numeral 0 in FIG. 1;

FIG. 3 is a bottom plan view of the numeral shown in FIG. 2; and

FIG. 4 is a rear elevational view of the numeral shown in FIG. 2.
